UNITED STATES PATENT OFFICE.

SAMUEL G. GREEN, OF GRAY, GEORGIA, AND JAMES L. HATCHER, OF THE UNITED STATES ARMY, WASHINGTON, DISTRICT OF COLUMBIA.

MOUNT FOR GUNS.

Application filed December 11, 1926. Serial No. 154,266.

(GRANTED UNDER THE PROVISIONS OF THE ACT OF MARCH 3, 1883, 22 STAT. L., 625.)

The invention described herein may be used by the Government, or any of its officers or employees in prosecution of work for the Government, or by any other person in the United States, without the payment to us of any royalty thereon in accordance with the act of March 3, 1883.

The subject of this invention is a mount for guns.

In employing anti-aircraft fire at the lower altitudes which are in the zone of the automatic type of weapons the target passes very rapidly and during the brief period in which it is in range a maximum fire must be delivered. In order that such fire may be accurately directed it is essential that the mount be of such nature as to provide stability while permitting rapid maneuvering.

While an elementary solution for obtaining a large volume of fire consists in massing guns, the multiple gun mounts heretofore provided are all lacking either in stability or facility of control and direction.

The multiple gun mount of the present invention provides for stability by mounting the guns forwardly of the cradle trunnions and by positioning the trunnions in the plane of the bores of the guns; it provides for accuracy in tracking and rapidity in maneuvering by permitting an arrangement of the sighting systems whereby the gun pointers may function from an unchanging position.

A novel firing mechanism by means of which the guns may be fired independently or as a unit and a novel manner of angularly diverging the guns with respect to each other are also features of this invention.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a view in side elevation of a gun mount constructed in accordance with the invention;

Fig. 2 is a view in rear elevation thereof; 55

Fig. 3 is a plan view;

Fig. 4 is a view in side elevation of Fig. 3;

Figs. 5, 6 and 7, are detail sectional views on the respective lines of Fig. 3;

Fig. 8 is a plan view of the saddle shown 60 in Fig. 6;

Fig. 9 is a sectional view on the line 9—9 of Fig. 4.

Referring to the drawings by numerals of reference:

The mount comprises a pedestal base 5 on which is rotatably mounted for all around traverse a top carriage 7 for which actuating mechanism 8 is provided. The top carriage is formed with a pair of enlarged bearings 70 9 receiving a trunnion 10 on which is mounted a cradle 11 consisting of a relatively thin flat plate having at its rear end a counterweight 12. The cradle is moved in elevation about the trunnion by means of a worm 13 75 actuating the worm wheel segment 14 fixed to the cradle.

The cradle is arranged and dimensioned to carry four standard caliber .50 machine guns evenly distributed across the cradle and all attached in a similar manner. In order that the guns may be moved vertically and laterally with respect to each other to vary the cone of fire, the attaching means consists of an adjustable trunnion cradle comprising a socket member 15 threaded in a tubular extension 16 fixed to the gun cradle 11. The socket member 15 receives the tapered stem 17 of a yoke 18 which is held in adjusted position by means of a nut 19 threaded on the lower end of the stem and loosened when it is desired to elevate the socket member without rotating the yoke. In order that the gun to be mounted may receive additional lateral displacement irrespective of the adjustment applied to the yoke the trunnion pin 20 which passes through and supports the gun is embraced by set screws 21 threaded in the yoke arms and contacting the gun whereby to move and hold 100 it in place on the trunnion pin.

The rear attaching means comprises a saddle 22 which receives the pin 23 inserted through the lugs 24 on the gun. The saddle is supported on a pair of brackets 25 being secured by screws 26 which pass through elongated slots 27. The saddle is spaced from the cradle to enable it to be shifted in

conforming to the lateral adjustment of the trunnion cradle. The attaching means are so arranged that the guns when in place are entirely forward of the cradle trunnion 10 and the plane containing the centers of bore of the guns intersects the trunnion at all positions of elevation.

At one side of each of the positions occupied by the guns the cradle is formed 10 with large openings 28 adjacent each of which are provided latches 29 on the under side for the purpose of retaining a magazine 30.

The trigger mechanism 31 of the standard 15 .50 caliber machine gun is of the thumb pressed type which is moved downwardly to release the firing pin. The particular firing mechanism which is provided to operate the triggers 31 consist of a number of concentric tubes 32 mounted in brackets 33 between the cradle trunnion and the rear of the guns and of a number corresponding to the number of guns. The outermost tube terminates adjacent the right hand gun, the innermost 20 tube extends over to the left hand gun and the intermediate tubes terminate opposite the intermediate guns. Each tube carries at 25 its extremity a firing arm or hammer 34 which acts to depress the trigger 31 on rotation of the tube. The actuating mechanism for rotating each of the tubes consists of the handles 35 which are preferably of different lengths to facilitate their selection. In order that the group of guns may be fired as a 30 unit a pin 36 may be inserted through aligning apertures in all of the tubes to cause them to be rotated together.

The gun pointers who operate the traversing mechanism 8 and the elevating mechanism 13—14 respectively sight through the azimuth sighting system 37 on which lateral deflection corrections are applied and measured on the scale 38 and through the elevation sighting system 39 on which vertical deflection corrections are applied and measured 40 on the scale 40. The arrangement of the entire mount is such that the rear sights may be in a relatively unchanging position, one being mounted at the trunnion 10 and the 45 other bearing a corresponding relation 50 through the links 41 and 42.

We claim:

1. A mount for guns embodying a base, a carriage mounted in the base for all around 55 traverse, a cradle trunnioned in the carriage, means on the cradle for mounting a plurality

of machine guns forwardly of the trunnion and in such position that the plane containing the centers of bore of all the guns will intersect the trunnion, means for counterbalancing the cradle, an elevating segment fixed to the cradle, means for actuating said segment and a sighting system mounted for movement with the cradle and having its rear end at a fixed point corresponding to the trunnion.

2. A mount for guns embodying a base, a carriage mounted in the base for all round traverse, a cradle trunnioned in the carriage, means on the cradle for mounting a plurality of machine guns forwardly of the trunnion and in such position that the plane containing the centers of bore of all the guns will intersect the trunnion, means for counterbalancing the cradle, an elevating segment fixed to the cradle, and means for actuating said segment.

3. A mount for machine guns embodying a carriage mounted for all around traverse, a cradle trunnioned in the carriage, means on the cradle for mounting a plurality of machine guns forwardly of the trunnion and in such position that the plane containing the centers of bore of all the guns will intersect the trunnion and means for counterbalancing the cradle.

4. In combination a cradle, a plurality of machine guns mounted in parallel relationship thereon, a firing mechanism including concentric tubes corresponding in number to the guns and one tube terminating adjacent each gun, a firing arm at such extremity, means whereby the tubes may be rotated independently and means for selectively grouping the tubes to operate as a unit.

5. An adjustable trunnion cradle embodying a support, a socket member threadable in the support, a yoke having a tapered stem inserted in said member, means for securing the stem in place, the trunnion pin passing through the arms of the yoke and a set screw threaded in each arm and embracing the pin.

6. An adjustable trunnion cradle embodying a support, a socket member threadable in the support, a yoke having a stem inserted in said member, means for securing the stem in place, a trunnion pin passing through the arms of the yoke and a set screw threaded in each arm.

SAMUEL G. GREEN.
